UNITED STATES PATENT OFFICE.

VICTOR WIERMAN, OF PITTSBURG, PENNSYLVANIA.

RAIL-SECURING DEVICE.

SPECIFICATION forming part of Letters Patent No. 531,819, dated January 1, 1895.

Application filed December 6, 1893. Serial No. 492,924. (No model.)

To all whom it may concern:

Be it known that I, VICTOR WIERMAN, of Pittsburgh, in the county of Allegheny and State of Pennsylvania, have invented a new and useful Improvement in Rail-Securing Devices, of which the following is a full, clear, and exact description, reference being had to the accompanying drawings, forming part of this specification, in which—

10 Figure 1 is a side elevation of a rail-fastening device constructed in accordance with my invention. Fig. 2 is a plan view; and Fig. 3 is a vertical cross-section on the line III—III of Figs. 1 and 2.
15 The object of my invention is to provide improved means for fastening railway and tramway rails to their ties or supports in such a manner as to permit them to be shifted and adjusted in position to secure the proper gage
20 of the track without disturbing the tie or support. The parts in the device are so arranged that they can be easily removed for their renewal without disturbing the bearing of the ties on the roadbed or injuring them by
25 driving additional holes into them as is necessary in most such devices. The construction is such as to hold the rail (and the tie-plate if used) tightly to the tie and to hold the whole tie from its lower surface upward
30 directly under the bearing of the rail, firmly connecting them together by the bolts, plates, &c., hereinafter described, making a strong and substantial structure.

In the accompanying drawings, 2 represents
35 a railway rail; 3, one of the ties; 4, a tie plate on which the rail rests; 5, 6, bolts which extend from a common horizontal pivot-pin or bolt 7 upward to opposite sides of the rail through the tie and through slots in the plate
40 4. These plates are preferably staggered somewhat, that is to say they are not placed opposite to one another, but the degree of their lateral separation may be determined in making the holes in the tie and tie-plates
45 according to the judgment of the engineer applying the same. The pin 7 fits in a transverse hole which extends through the tie and intersects the lower portions of the holes made for the bolts 5, 6, so that after these bolts are
50 set in place the pins can be inserted through eyes, hooks, or other securing device at their lower ends, and that the bolts will then have

capacity for some radial oscillatory movement within the holes in which they are fitted.

For the purpose of giving greater strength 55 and firmness to the connection of the bolts 5 and 6 with the tie, I prefer to apply to the bottom of the tie a U-shaped clip-plate 8, the branches of which fit on opposite sides of the tie and have holes through which the pin or bolt 7 passes. The connection of the bolts with the tie is rendered by this clip-plate very strong, since it practically makes the whole body of the tie between the plate 8 and the rail effective in taking the strain. The use 65 of a bottom plate for the tie in combination with rail-holding bolts of any construction is therefore claimed by me broadly. The clip-plate 8 is also preferably provided on the bottom with downwardly projecting flanges 9, 70 which, by fitting in the ballast of the permanent way, tend to prevent longitudinal shifting of the tie. At the upper end of the bolts 5 and 6 are wedge-shaped clips or blocks 10, having enlarged holes or slots through which 75 the bolts pass and fitting on the tie-plate 4 and over the edges of the rail flanges. Nuts 11 are applied to the bolts, and when screwed down upon the inclined faces of the clips or blocks 10, press them inwardly and downwardly against the flanges of the rail so as to hold the latter firmly to the tie. The lateral adjustment of the rail upon the tie may be accomplished readily by loosening the nuts 11 on one side of the rail, and tightening the 85 nuts on the other side, the effect of which is by pressing on the blocks to shift the rail laterally.

The ease by which the track can be gaged accurately without the necessity of drawing 90 and inserting spikes, constitutes a very important advantage of my improvement, since the use of spikes by making in the tie holes in which the water can collect, causes the tie to rot rapidly, and, furthermore, a multitude of 95 holes impairs the security by which the rail is held in place and shortens the life of the tie.

My improved device is simple in construction. It is easily applied and easily adjusted, and has desirable qualities of strength and durability. The bolts 5 and 6, pin 7, tie-plate 4, clips 10 and nuts 11 may be removed at any time without disturbing the tie or its bearing on the roadbed, thus enabling the rails and tie-

plates, or any of the other parts above mentioned, to be changed or renewed without disturbing the tie or its bearing, and without injuring it by making fresh holes in the tie by drawing and replacing spikes as heretofore.

My invention may be applied not only to wooden ties, but to metal ties of various constructions.

Within the scope of my broader claims, instead of using a single pin or bolt 7 for both bolts 5 and 6, I may provide the latter bolts with separate holding pins. The location of the pin or pins 7 may be changed, but in all cases it should be below the surface of the top 15 of the tie, whether it passes directly through the body of the tie, or beneath its lower surface.

It should be understood that within the scope of my broader claims, many changes in the construction and arrangement of the parts may be made by the skilled mechanic. For example, the plate 4 and clip-plate 8 may be omitted or substituted by equivalent constructions, and other changes may be made, and 25 other fastening devices may be used for holding the bolts 5 and 6, instead of the pin 7.

I claim—

1. As means for holding a rail to its tie, holding bolts which are inserted obliquely in 30 the tie and pivotally engage a single transverse pin or bolt, said holding bolts having

nuts to engage the base of the rail, substantially as described.

2. As means for holding a rail to its tie, holding bolts which are inserted obliquely in 35 the tie and are provided with clips for engaging the rail, and a transverse bolt extending through registering eyes in the holding bolts, whereby the rail may be adjusted, substantially as described.

3. As means for holding a railway rail to its tie, a metal bottom plate which fits beneath the tie, and bolts for holding the rail, said bolts being connected with said bottom plate, whereby the bottom plate serves as a strong 45 bearing for said bolts, and as a lower bearing for the tie; substantially as described.

4. As means for holding the rail to its tie, oscillatory holding-bolts which are inserted from above in holes in the tie and are held 50 by a transverse holding pin or bolt situate below the upper surface of the tie, slotted clips or blocks on the bolt, and means for pressing them against the rail to hold the same and to permit its lateral adjustment; substantially 55 as described.

In testimony whereof I have hereunto set my hand.

VICTOR WIERNAN.
